FOLDABLE TRAVERSING SCREEN

James Hirashiki, Los Angeles, Calif., assignor to Universe Products Company, Los Angeles, Calif., a limited partnership

Filed Feb. 9, 1962, Ser. No. 68,753

Term of patent 14 years

(Cl. D54—2)

Fig. 1.

Fig. 2.

FIGURE 1 is a perspective view of a foldable traversing screen showing my new design.

FIGURE 2 is a perspective view on a larger scale of a repeating individual block comprising the screen.

The rear of the screen not shown is substantially the same as the front shown except in reverse.

I claim:

The ornamental design for a foldable traversing screen, substantially as shown and described.
